UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

TYPOGRAPHICAL MACHINE.

1,115,181.

Specification of Letters Patent.

Patented Oct. 27, 1914.

Original application filed October 6, 1911, Serial No. 653,128. Divided and this application filed November 26, 1912. Serial No. 733,581.

To all whom it may concern:

Be it known that I, HEINRICH DEGENER, a subject of the German Emperor, residing at 26 Hollmannstrasse, Berlin, in the German Empire, have invented new and useful Improvements in Typographical Machines, of which the following is a specification, being a division of an application filed by me on the 6th day of October, 1911, Serial 10 No. 653,128.

My invention relates to typographical composing machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started.

More particularly, the invention relates to the mold carrier or disk, which is ordinarily provided with two or more molds of different size, any one of which may be brought into operative position, as desired. In ordinary practice, this disk is actuated by a pinion which receives its motion from a pin or stud on a collar fast on the driving shaft; and in order to change the mold, it is necessary to shift the pinion forward by hand, thereby disengaging it from the driving pin or stud, and then to turn it relatively to or independently of the shaft in order to rotate the disk and bring another mold into operative relation to the other parts, after which the pinion is again engaged with the pin. In order to avoid the inconvenience of this method of adjustment, I preferably employ a normally disengaged hand crank or equivalent device, arranged in such manner that its actuation serves both to draw the pinion forward and then to rotate it to adjust the disk, after which the crank or other member is automatically disengaged and remains at rest.

In the accompanying drawings, I have shown my improvements as employed in connection with the ordinary form of ac-

tuating means for the mold carrier, but obviously they may be employed in connection with other forms with similar effect. It will also be understood that my improvements may themselves partake of different embodiments, which will suggest themselves to those skilled in the art to accord with the varying uses to which they may be put and still be comprised within the scope of the invention.

Figure 1 is a front elevation of the improved means for effecting a change of mold; Fig. 2, a transverse section on the line 2—2 of Fig. 1; Fig. 3, a horizontal section on the line 3—3 of Figs. 1 and 2; Fig. 4, a rear elevation of a detail; and Fig. 5, a sectional side elevation of the driving pinion for the mold carrier.

1 is the mold carrier; 2, one of its molds; 3, its driving or actuating pinion loose on the driving shaft 4; 5, the clutch fast on the shaft 4 to hold the pinion 3 to the latter; 6, the clutching pin; 7, its socket in the pinion 3; 8, the introducing groove; and 9, the reengaging spring resilient between a shoulder 10 on the boss 11 of the actuating pinion and a shoulder 12 fast to the shaft 4. All the foregoing parts are substantially as heretofore.

23 is a hand crank fast on the front end of a countershaft 24 rotatable in a bracket 25 fast to the machine frame.

26 is a collar fast on the shaft 24 and having a cam surface 27 operative in the vertical plane.

28 is an arm pivoted on the bracket 25 and provided with two fingers 29, 30, carrying rollers. The finger 29 engages in an annular groove 31 in the periphery of the boss 11 and the finger 30 with the cam surface 27 with which it is kept in contact by the spring 9.

32 is a spur wheel loose upon the shaft 24 and in gear with the pinion 3. It has more teeth than the latter, the excess quantity being a whole number which is also an aliquot part of the quantity of teeth on the pinion 3. Thus, if the latter has 24 teeth, the wheel 32 may have an excess quantity of four, *i. e.*, of one sixth—28 in all. There is a clutch between the shaft 24 and the wheel 32 consisting of a pin wheel 33 fast on the said wheel and having a pin 34 for each aliquot part of the number of teeth

in the wheel 32, the respective aliquot part (4 teeth) or a total of seven pins (Fig. 4), each pin being positioned after the respective aliquot part (4 teeth).

5 35 is a clutching finger fast on a slide 36 working in a slot 36^a in the collar 26 parallel with the axis of the latter and having the same radius as the pins 34. The presence of the finger 30 in the recess of the 10 cam surface 27, keeps the finger 35 out of engagement with the pin wheel 33, against the resilience of a spring 37.

The improvement acts as follows. A rotation of the hand crank 23 in the direction 15 of the arrow in Fig. 1, makes the right-hand rise of the cam surface 27 swing the arm 28 to the front far enough to disengage the pinion 3 from the clutching pin 5 and, therefore, from the driving mechanism of the 20 machine, against the resilience of the spring 9, while the spring 37 pulls the finger 35 into engagement with the next pin (Fig. 4) on the pin wheel 33 thereby locking the wheel 32 to the said crank. The completion 25 of the rotation of the latter, turns the pinion 3 through one rotation, bringing its socket 7 opposite the pin 6 and the cam surface 27 opposite the finger 30, whereupon the spring 9 reengages the pinion 3 with the driving mechanism of the machine and 30 also the finger 30 in the recess in the cam surface 27, making the said finger disengage the finger 35 from the pin wheel 33.

Having thus described my invention, its 35 construction and mode of operation, what I claim and desire to secure by Letters Patent of the United States is as follows:

1. In a type bar casting machine, the combination with a mold carrier adapted to be 40 equipped with a plurality of molds, its driving pinion, the driving mechanism of the machine, and a clutch between the said pinion and mechanism, of a hand crank and means by which the continued movement of 45 said crank in the same direction, firstly, opens the said clutch and secondly, by turning the said pinion, effects a change of mold.

2. In a type bar casting machine, the combination with a mold carrier adapted to be 50 equipped with a plurality of molds, its driving pinion, and driving mechanism of the machine, and a clutch between the said pinion and mechanism, of a hand crank and means by which one revolution of the said 55 crank, firstly, opens the said clutch and secondly, turns the said pinion through one revolution thereby effecting a change of mold.

3. In a type bar casting machine, the combination with a mold carrier adapted to be 60 equipped with a plurality of molds, its driving pinion, the driving mechanism of the machine, and a clutch between the said pinion and mechanism, of a hand crank, a shaft 65 upon which the crank is mounted, a gear

wheel loose upon the shaft thereof and in direct mesh with the said driving pinion, means by which the first portion of the movement of the crank and its shaft opens the said clutch and means by which the gear 70 wheel on the shaft of the hand crank is held to it.

4. In a type bar casting machine, the combination with a mold carrier adapted to be 75 equipped with a plurality of molds, its driving pinion, the driving mechanism of the machine, and a clutch between the said pinion and mechanism, of a hand crank, a shaft upon which said crank is mounted, a wheel loose on the shaft thereof in gear with the 80 said driving pinion and carrying a definite quantity of teeth more than the latter, a clutch operative between the said shaft and loose wheel, and means for closing the said clutch as soon as the crank has been turned 85 through an arc equal to the said quantity of teeth.

5. In a typographical machine, the combination of a movable mold carrier, driving means for moving the carrier in the ordinary 90 operation of the machine, actuating mechanism connected thereto, and manual devices, normally disconnected from the driving means, and operable first to break said actuating connection and thereafter to 95 operate the driving means to adjust the carrier to a different position.

6. In a typographical machine, the combination of a rotary mold carrier, a driving pinion for rotating the carrier in the ordinary 100 operation of the machine, a shaft for the driving pinion, manually rotatable devices normally disconnected from the driving pinion for operating it at will to adjust the carrier to a different position, and means 105 whereby the rotation of said devices will break the connection between the pinion and shaft and establish a connection between the pinion and the said devices.

7. In a typographical machine, the combination of a movable mold carrier, driving means for moving the carrier in the ordinary 110 operation of the machine, actuating mechanism connected thereto, manually operable devices, normally disconnected from the driving means, for operating them at will to adjust the carrier to a different position, and means whereby the operation of said devices 115 will break said actuating connection and establish a connection between the driving 120 means and the said devices.

8. In a typographical machine, the combination of a movable mold carrier, driving means therefor, and adjusting devices serving by a single movement in the same direction first to break the connection between the carrier and its driving means and thereafter to adjust the carrier to a different position.

9. In a typographical machine, the combi- 130

nation of a movable mold carrier, driving means therefor, and rotary devices serving by their continued rotation first to break the actuating connection between the carrier and its driving means and thereafter to alter the position of the carrier.

10. In a typographical machine, the combination of a movable mold carrier, driving means therefor, and adjusting devices serving by their continued movement in the same direction first to break the driving connection between the carrier and its driving means and thereafter to operate the said driving means to adjust the mold carrier to a different position.

11. In a typographical machine, the combination of a movable mold carrier, driving means therefor, and rotary devices serving by their continued rotation first to break the driving connection between the carrier and its driving means and thereafter to operate the driving means to alter the position of the carrier.

12. In a typographical machine, the combination of a movable mold carrier, driving means therefor, actuating mechanism connected thereto, and manual devices capable of moving relatively to and of moving conjointly with the said driving means, and adapted by said relative movement to break the said actuating connection, and by said conjoint movement to operate the driving means to alter the position of the carrier.

13. In a typographical machine, the combination of a movable mold carrier, driving means therefor comprising a driving pinion, and rotary devices capable of rotating relatively to and of rotating conjointly with the driving pinion, and adapted by said relative rotation to break the driving connection between the carrier and the driving means, and by said conjoint rotation to operate the pinion to alter the position of the carrier.

14. In a typographical machine, the combination of a movable mold carrier, driving means for moving the carrier in the ordinary operation of the machine, and independent manual devices, normally at rest, for operating the driving means at will to adjust the carrier to a different position, together with means to restore said devices to their normal position of rest after said adjustment has been effected.

15. In a typographical machine, the combination of a movable mold carrier, driving means for moving the carrier in the ordinary operation of the machine, and manual devices normally disconnected from the driv-

ing means and adapted to be connected thereto at will so as to operate the same to adjust the mold carrier to a different position, together with means tending constantly to disconnect said devices from the driving means.

16. In a typographical machine, the combination of a mold carrier, driving means therefor comprising a shaft and actuating pinion, the said pinion being rotatable independently of the shaft to alter the position of the carrier, a loosely-mounted adjusting pinion meshing directly with the actuating pinion, and manual devices for operating the adjusting pinion at will to effect the aforesaid independent rotation of the driving pinion.

17. In a typographical machine, the combination of a mold carrier, driving means therefor comprising a driving pinion, a loosely-mounted adjusting pinion meshing with the driving pinion, and manually-operated devices to break the driving connection between the carrier and the driving means and to operate the adjusting pinion so as to alter the position of the carrier through the medium of the driving pinion.

18. In a typographical machine, the combination of a mold carrier, driving means therefor comprising a driving pinion, a loosely-mounted adjusting pinion meshing with the driving pinion, and rotary devices serving by their rotation first to break the driving connection between the carrier and the driving means, and thereafter to establish a connection between themselves and the adjusting pinion, so as to adjust the mold carrier through the medium of the driving pinion.

19. In a typographical machine, the combination of a mold carrier, driving means therefor comprising a shaft and actuating pinion, a clutch between said shaft and pinion, a second shaft, an adjusting pinion loosely mounted thereon and meshing directly with the driving pinion, a clutch between said second shaft and adjusting pinion, and means whereby the opening of one of the clutches effects the closing of the other.

In witness whereof, I hereunto set my hand this 8th day of November, 1912, in the presence of two attesting witnesses.

HEINRICH DEGENER.
